ATTACHMENT PLUG AND RECEPTACLE

Wilbur K. Mess, Newark, N. J.

Application March 12, 1934, Serial No. 715,046

3 Claims. (Cl. 173—330)

The general objects of this invention are to provide a combination of attachment plug and receptacle, which will be inexpensive, easily manufactured, assembled and installed, in which the 5 current carrying parts will be well-insulated and the device therefore safe in use.

In the usual combination, care must be exercised to bring the projecting blades of the plug into register with the spaced slots in the receptacle, making it difficult to use such apparatus in the dark or in out of the way places. These blades also have a tendency to bind in the receptacle and prevent the plug from coming loose with pull on the cord as intended with connectors 10 of this type.

Special objects of the present invention are to overcome the latter objections and to provide a combination structure in which the plug may be properly engaged with the receptacle in all angularly or relatively rotated positions of the plug and in which the plug may be rotated in the receptacle and readily come away from the receptacle by pull on the cord.

The foregoing and other desirable objects are 25 attained by the novel features of construction hereinafter described and claimed and illustrated in the accompanying drawing.

In the drawing, the invention is shown embodied in one practical preferred form, but it is 30 to be understood that the actual physical structure may be modified as regards this disclosure, all within the true intent and broad scope of the claims.

Fig. 1 is a face view of a double receptacle such 35 as mounted in a wall box.

Fig. 2 is an enlarged broken vertical sectional view as on line 2—2 of Fig. 1 and showing the receptacle and plug in combination.

Fig. 3 is an end view of the plug member of the 40 combination.

Fig. 4 is a broken rear elevation of the double receptacle.

Fig. 5 is a longitudinal sectional view of an 45 adapter base for accommodating the plug to a screw socket type of receptacle.

The receptacle illustrated consists of a single 50 unitary base of insulating material having the somewhat rounded enlargements 6, at opposite ends connected by a reduced intermediate portion 7.

At the exposed face of the receptacle base are 55 conical depressions 8, providing access through reduced passages 9, to center receptacle terminals 10.

The latter are illustrated as cupped split spring members of generally globular shape with re-entrant bends 11, and outwardly and backwardly bent ends 12. These spring cups are of a size to 60 be forced forwardly through the passages 13, in the back of the base and to thereupon enlarge or

spring outwardly into enlargements 14, with the rearwardly bent portions 12 interlocked with shoulders 15.

In the double type receptacle such as illustrated, the center contacts last described may be connected by a bar 16, and the latter may have a bent up lug 17, lying at one side of the reduced intermediate portion of the base and carrying a terminal screw 18.

Surrounding the center conical cavity of the 10 receptacle is a narrow concentric groove 19, and extending into this groove at one or more points is the outer contact 20.

In the double receptacle shown, the two outer 15 contacts are in the form of angularly bent lugs 15 on opposite ends of a bar member 21.

This double contact member, like the other is held in place by introverted or backwardly bent 20 portions 22, at the ends of the contact lugs engaging undercut shoulders 23. These contacts therefore can be secured in position by simply 25 forcing them through the holes 24, in the back of the base until the bent spring ends 22, snap in front of the holding shoulders 23.

As shown in Fig. 1, the side contacts 20 are 25 preferably rounded substantially to the curvature of the annular slots 19, so as to snugly engage the ring contacts on the plugs which enter these slots.

The plug member is shown in the form of a 30 substantially flat disc 25, carrying a projecting ring contact 26, to fit in the annular slot of the receptacle and frictionally engage the curved contact lug 20. The exposed edge of this ring is shown as beveled at 27, to cut its way past 35 dust or other possible obstruction in the annular groove and force back the curved spring contact, substantially as shown at the top in Fig. 2.

Projecting from the center of the insulating 40 disc in concentric relation to the ring contact is a center contact stud 28, having a rounded nose 29, to pass through the central guide opening 9, into the spring contact socket at the back of the same.

The center plug contact is longer than the ring 45 contact, so that it may be used as a guide pin entering the conical socket 8 of the receptacle and sliding on through the central guide passage 9, to thereby bring the ring contact into position for 50 register with the annular groove and into engagement with the side contact 20, extending into said groove.

The center and side contacts of the plug may 55 be secured by knurling or roughening the same as indicated at 30, and by molding the plug base about the same.

The ring contact may be cut from tubing or be 60 made from strip stock rolled into circular form, with the ends secured together or not, in accordance with the desired stiffness or springiness

to be given the contact. In Fig. 2, the material of the ring contact is shown doubled back upon itself at 31, at the back of the plug, to provide sufficient thickness for the screw seat 32, taking 5 the terminal screw 33, for one of the wires of the electric cord 34.

The center plug contact is shown as drilled or otherwise constructed as hollow from the back end and as internally screw-threaded at 35, to 10 receive the binding screw 36, for the other cord wire.

The terminal screws and back of the plug disc may be covered over by a flexible rubber sheath 37, sprung over a shouldered portion 38, of the 15 disc. The neck of this sheath is shown as having a perforated diaphragm 39, designed to grip the cord so as to make a water-proof joint and afford a strain relief for the terminal screws.

The side contacts 20 are shown in Fig. 4 as 20 having a single terminal lug 40, extended from one side of the connecting bar 21, and bent up at the side of the narrow portion of the receptacle base opposite the first terminal lug 17. Lug 40 is shown as carrying the terminal screw 41. This 25 and the other terminal screw 18 are indicated as extending into holes 42, molded in the sides of the base, these screws then serving as additional means to prevent the contacts coming away from the receptacle base.

30 A yoke 43 is indicated in Figs. 1 and 2 for mounting the receptacle in the box 44, and this yoke also is held to the receptacle base without screws by making it with punched in lugs 45, in the side arms of the same entering corresponding openings 46, molded in the ends of the base. The side arms of this yoke are shown angled or offset at 47, to stand in back of the end corners of the receptacle base and thereby solidly support 35 the base apart from the support afforded by the 40 lugs 45.

In order that the new plug may be used with 45 existing receptacles of the standard screw socket type, adapters such as indicated in Fig. 5 may be employed, the same being constructed with the conical guide sockets and other features of the new receptacles described, but having screw terminals 48 and center contacts 49, for cooperation with the usual screw socket contacts. In this particular view, the screw terminal 48 is 50 shown as having the curved side contact lug 20' connected therewith and the center contact is shown as having the central spring socket contact 10' connected with the same.

This adapter provides the same facilities as 55 the receptacle, having the conical throat 8' and guide passage 9' for directing the central prong of the plug to the center spring contact 10' and for locating the ring contact 26 with respect to the annular groove 19' and the side contact 20' 60 projecting thereinto.

The invention it will be seen makes it possible to enter the plug in any relatively rotated position of the same and to "find" the proper location by simply sliding the plug over the face of the receptacle until the prong enters the conical depression, whereupon a straight inward push will then suffice to solidly couple the contacts. The glove fastener type of center contact in the receptacle resiliently holds the plug in position, but a pull on the cord from practically any angle is effective to disconnect the plug from the 65 service contacts. The receptacle parts can be 70

assembled by simply pushing the side and center contacts through from the back of the base so that they snap over the holding shoulders 23 and 15. The binding screws 18 and 41 when turned into the openings 42 in the sides of the base, lock these contact elements in their previously secured relation. These terminal screws may have screw seats in the angled lugs 17 and 40 of the contact members, or if desired, these screw seats may be provided by metallic inserts 50, 10 molded or otherwise fixed in the sides of the base member. The mounting yoke 43 may be engaged by forcing it over the back of the base until the projections 45 thereon snap into the recesses 46, 15 in the ends of the base. Then when the yoke is mounted in the box and held against spreading by the securing screws 51, Fig. 1, the yoke will be held interlocked with the base, so that one can not come away from the other.

The entire structure is simple and inexpensive, easily assembled, practical and safe and accomplishes the objects intended. The structure is susceptible of modification in various ways as will be apparent from the scope of the following claims. Such modifications may include reversal 25 of parts and the like, for instance, the ring contact member might be mounted on the receptacle part instead of on the attachment plug part.

What is claimed is:

1. An electric receptacle base having a flush 30 face with a generally conical prong guiding recess therein, a guide passage extending back from said recess, a larger chamber at the back of said guide passage and an annular groove in the flush face portion surrounding the conical recess, 35 and contacts located respectively in said chamber and annular groove, said chamber and annular groove being open through to the back of the base, said contacts being entered from the back of the base into said chamber and groove respectively, said chamber and groove having shoulders and said contacts having resilient locking portions engaging over said shoulders.

2. An electric receptacle, comprising a base 45 having substantially circular end portions connected by a narrower neck portion, said base having prong guiding sockets in the face of the same concentric with said generally cylindrical portions and annular recesses about said prong guiding sockets, contacts entered in said annular recesses and connected by a bar having a terminal lug at one side of the narrower neck portion of the base and center contacts in line with the guide sockets and connected by a bar having a terminal lug disposed at the opposite 55 side of the narrower neck portion of the base.

3. An electric receptacle, comprising a base structure having a substantially flush face with spaced generally conical prong guiding sockets and concentric annular grooves about said sockets, prong receiving center contacts on the base at the back of said prong guiding sockets, a short terminal bar connecting said center contacts and provided with terminal means, a shorter terminal bar on the back of the base extending between the closest portions of the annular grooves and provided with terminal means and side contact elements connected with the ends of said shorter bar and disposed in said nearest portions 60 of said annular grooves.
